COMBINED PENCIL SHARPENER AND CLIP

Mark H. Lemieux, Toronto, Ontario, Canada, assignor to Mark H. Designs, Toronto, Ontario, Canada

Filed June 11, 1974, Ser. No. 478,546

Term of patent 14 years

Int. Cl. D19—06

U.S. Cl. D19—73

FIG. 1 is a perspective view of a combined pencil sharpener and clip showing my new design;

FIG. 2 is a second perspective view showing the other longitudinal side and bottom surface thereof.

I claim:

The ornamental design for a combined pencil sharpener and clip, as shown and described.
